Des. 1296

Walter W. Stanard, of Buffalo, N.Y.

Assignor to
Sherman S. Jewett & Francis B. Root, of same place
Letters, Patent No 1296, dated July 31, 1860.

The schedule referred to in these Letters Patent and making part of the same,

To all whom it may concern;
Be it known that Walter W. Stanard, of the City of Buffalo,
County of Erie, and State of New York, have invented or produced a new and original
Ornamental Design for Cooking Stoves, and I do hereby declare that the following
is a full clear and exact description of the same, reference being had to the accom-
panying drawings (photographic) and the letters of reference marked thereon.

Fig. 1. Represents the side plate of the stove.

(a) is the large oven door. It is surrounded by quarter and
half round and quarter concave mouldings (b).

The panel of the door is ornamented by a central rosette consist-
ing of a central ovate bead (c) and embossed leaves (d) forming a square with
leaf like sides diagonal to the panel.

(e) is the small oven door, surrounded by quarter and half

round and quarter concave mouldings, f, similar to the mouldings surrounding the large oven door. Its panel is ornamented by a central rosette with a central ovate head (g) and embossed leaves (h) similar to those of the central rosette on the large oven door, but elongated to an elliptic form to correspond to the panel.

I is the door of the fire chamber, surrounded by similar mouldings and having a similar central rosette to the small oven door (e) the rosette being made to correspond to the size of the panel.

The upper edge of the plate has a half round scroll scalloped moulding (i) with leaf like points (k). The lower edge has a broad moulding (l) with a denticulated edge and ornamented with reversed leaves (m) - (n) are bead mouldings near the back edge of the plate joining together and surmounted by spearheads (o).

Fig. II. Is the front plate of the stove with sliding doors (p, p) the jambs on either side of which have panels (q) with diamond shaped reticulations the upper edge of the plate over said panels having a scroll scalloped moulding (r) with leaf like points similar to the moulding at the upper edge of the side plate. Fig. I. The sliding doors (p, p) are surrounded by mouldings similar to those described as surrounding the doors in (Fig. I) and having similar central rosetts but rectangular in outline and arranged diagonally to the panels. Over these panels are rectangular panels (s) with diamond shaped reticulations and surrounded by bead mouldings. (t).

Having thus described my ornamental design for Cooking Stoves, what I claim and desire to secure by letters patent, is the ornamental figures and mouldings upon the plates of the stove, formed and arranged in relation to each other as herein described and shown in the accompanying drawings.
